UNITED STATES PATENT OFFICE.

JOHN MURPHY McCONNELL, OF ANDERSON, SOUTH CAROLINA.

DESIGN FOR A LANDSIDE FOR PLOWS.

SPECIFICATION forming part of Design No. 16,996, dated November 23, 1886.

Application filed October 12, 1886. Serial No. 216,071. Term of patent 14 years.

To all whom it may concern:

Be it known that I, JOHN MURPHY McCONNELL, a citizen of the United States, residing at Anderson, in the county of Anderson and State of South Carolina, have invented and produced a new and original Design for Land-sides for Plows; and I do declare the following to be a full, clear, and exact description of the same, reference being had to the accompanying drawings, forming a part thereof.

The accompanying drawings illustrate my new design for a landside. Figure 1 is a front perspective view of my landside, and Fig. 2 is a rear perspective view of the same.

The design of my landside is described as follows: The outer face, 1, of the wing 2 is straight and even, and has an upward extension, 3, the outer face of which is flush and even with the outer face of the said wing. The rear end of the said wing is nearly V shape—that is, it gradually becomes narrower until it nearly comes to a point. Rising from the lower edge and inner face of the rear end of the said wing 2 is a V-shaped flange, 4, which stands at right angles with the inner face of said wing. The larger end of this flange 4 is flush with the rear end of said wing, and it gradually tapers until its smaller end disappears at a point about one-fourth the distance of the entire length of the wing from the front edge of the wing. This flange 4 is about the same thickness of the said wing. The front end of said wing is slightly concave. Rising from the front end of said wing, and standing

at right angles with the inner face of the same, 35 is a flange, 5. This flange is the same thickness that the said wing is, and is the same thickness throughout its entire length and breadth, and it is bent or concaved so that its front face exactly conforms to the front end of 40 said wing 2, and its lower end is exactly flush with the lower edge of the said wing, and its upper end is flush with the upper end of the upward extension, 3. In the center of this flange 5 is a slot, 6, which is about one-half as 45 long as the said flange.

Having described my new design for a landside, what I claim is—

The design for a landside, the same consisting of the wing 2, having the upward extension, 3, its rear end tapering nearly to a point and its front end being concave or circular, the V-shaped flange 4, rising perpendicular from the lower edge and inner face of the said wing, and the flange 5, rising from the front 55 end and perpendicular to the inner face of the said wing, its lower end being flush with the lower edge of the said wing and its upper end with the upper end of the extension 3 and conforming to the circle of said end, and having 60 in its center the slot 6, as shown.

In testimony whereof I affix my signature in presence of two witnesses.

JOHN MURPHY McCONNELL.
